UNITED STATES PATENT OFFICE.

EARL LEON CRABB, OF CHICAGO, ILLINOIS, ASSIGNOR OF ONE-HALF TO GEORGE M. HOKE, OF CHICAGO, ILLINOIS.

AUTOMATIC FILM-FIRE EXTINGUISHER.

1,187,124.

Specification of Letters Patent. Patented June 13, 1916.

Application filed November 29, 1915. Serial No. 64,147.

To all whom it may concern:

Be it known that I, EARL L. CRABB, a citizen of the United States, residing at Chicago, in the county of Cook and State of Illinois, have invented a new and useful 5 Automatic Film-Fire Extinguisher, of which the following is a specification, reference being had to the accompanying drawings, and to the letters and figures of reference marked thereon.

This invention relates to moving picture projecting machines in which inflammable ribbon-like films are used to carry the pictures between an object lens and powerful 15 projecting-light rays, the invention having reference more particularly to means for extinguishing the fire in case the film becomes ignited by the light rays.

An object of the invention is to provide 20 means for effectively and reliably extinguishing the fire on a moving picture film in the shortest possible amount of time, in order to preserve nearly all of the film and thus avoid serious loss.

Another object is to provide an automatically-operating and reliable film-fire-extinguisher of such construction as to be adapted 25 to operate as closely as possible to the point at which the film passes the light rays in a picture projecting machine, in order that the fire may be extinguished promptly and as soon as it may be possible after 30 ignition of the film occurs.

A further object is to provide an improved 35 mechanical film-fire-extinguisher of such construction as to be controlled by means of a medium that shall be susceptible of being acted upon by heat developed by the burning film, and which extinguisher shall be adapted to be connected to a magazine or reel house.

With the above-mentioned and other objects in view, the invention consists in providing a moving picture projecting machine 45 with an appliance for extinguishing or arresting the progress of a fire when the picture film becomes ignited in passing the powerful projecting light rays; the invention consisting further in the novel parts, 50 and combinations and arrangements of parts, as hereinafter particularly described and further defined in the accompanying claims.

Referring to the drawings,—Figure 1 is a 55 side elevation of a moving picture film ar-

ranged as when in use in connection with its magazines partially broken away, the projecting machine through which the film passes being shown by broken lines and the necessary source of light symbolically indicated, two of the improved fire-extinguishers being illustrated in convenient arrangement relatively to the machine for arresting the progress of fire on the film and preventing the fire from entering the magazines; Fig. 2 is a fragmentary vertical central section showing the upper magazine and the upper portion of the projecting machine and the course of the film, one of the improved fire-extinguishers being shown in a convenient position; Fig. 3 is a perspective view of the improved fire-extinguisher as preferably constructed to be restrained from action preferably by means of a fusible or a combustible device that may be ruptured and destroyed by the flame or heat of a burning film; Fig. 4 is a plan view of a restraining link as preferably constructed; Fig. 5 is a fragmentary sectional view of the projecting machine and magazines provided each with a fire-extinguisher as preferably constructed at which a film fire is assumed to have been extinguished, as when the portion of the film between the fire-extinguishers has been burned away; Fig. 6 is a fragmentary section of the improved appliance approximately on the line A A on Fig. 5; Fig. 7 is a fragmentary external view of the fire-extinguishing appliance partially in section; and, Fig. 8 is a rear plan view of the appliance as preferably constructed.

Similar reference characters on the different figures of the drawings indicate corresponding elements or features of construction herein referred to.

In order that the purpose, relative arrangement, function and mode of operation of the invention may be clearly understood, the more essential features of a projecting machine of the class to which the invention is applicable are briefly pointed out, the machine usually comprising a table 1 on which a frame 2 of the operating mechanism is mounted, the upper magazine 3 being supported above the machinery frame and the lower magazine 4 beneath the table; 5 indicating an electrical lamp, 6 the usual condensing lens, 7 the light rays concentrated at the point 8 where the picture film passes an opening in the machinery frame, and 9

the object lens. The upper magazine has a reel 10, the lower magazine a reel 11, a film 12 being connected to both of the reels and extending through the machinery frame in which the film is suitably guided. The bottom of the upper magazine 3 has a slot 13 through which the film extends, and the top of the lower magazine has a slot 14, the table having a continuing slot 15 through which the film extends.

10 The film is driven or fed by a toothed wheel 16 arranged in the upper portion of the frame 2, the wheel assisting in guiding the film, and a similar wheel 17 is arranged 15 in the lower portion of the frame and drives or feeds and guides the film in proximity to the lower magazine. A guide roll 18 is arranged in the upper magazine adjacent to the slot 13, a guide roll 19 being arranged 20 in the lower magazine adjacent to the slot 14, to guide the film through the slots. In some cases a pair of guide rolls 20 and 21 are arranged adjacent to the outer end of the slot. It will be understood that the 25 guide rolls are spool-shaped or have flanges that are in contact with only the marginal portions of the film so as to guard against scratching the pictures on the film, and therefore the guide rolls are incapable of 30 preventing the progress of fire on the film past the rolls. During the operation of the projecting machine the ribbon-like picture film 12 may ignite at the window or opening of the frame 2 at 8, in case the light 35 rays are excessively strong or incorrectly focused, a portion of the film being inevitably consumed and thus destroyed.

The improved film-fire-extinguisher contemplates the extinguishing or arresting the 40 progress of the fire on the film as promptly as it may be practically possible after ignition of the film occurs, the particular position of the fire-extinguisher appliance depending upon available space for its accom- 45modation in existing operating machines or special designing of the machines to afford desirable space for the appliance.

The invention contemplates also restraining 50 means for preventing action of the extinguisher until required, such restraining means to be of such character or form as to be influenced and acted upon by heat or flames of the burning film to release the fire-extinguishing means for automatic 55 action.

In practically carrying out the objects of the invention a simple, inexpensive, positive and reliable form of construction and arrangement is shown as illustrative of the in- 60 vention, two of the extinguisher appliances 22 and 23 for the projecting machine being provided, one beneath the upper magazine 3 and the other upon the lower magazine 4, or as particularly shown, upon the table 1 65 within the frame 2 of the machine. The

extinguisher appliances are identically alike but reversed in relative arrangement. Each extinguisher appliance comprises a barrier capable of preventing the advance of fire past it on a film extending through the 70 barrier, which in the present case is in the form of a guard adapted to prevent the entrance of fire through the slot that is provided in the magazine for the passage of the film. As preferably constructed the 75 guard comprises two side walls 24 and 25, a front or fire-wall 26 and a front wall 27 connected to or formed integrally with the side walls, the latter being spaced apart so as to provide space between them for the 80 free movement of the film. The guard has projecting base plates 28 and 29 provided with bolt holes 30 and 31 respectively to receive bolts 32 and 33 whereby one of the guards is secured to the under side of the 85 bottom of the upper magazine 3 so as to cover the slot 13 and also the guide rolls 20 and 21 if present, the other one of the two guards being secured upon the table 1 by means of securing devices 34 and 35 so 90 as to cover the slot 15. The fire wall 26 is of suitable length so as to terminate, near the guided film and its end has an outwardly extending abutment bar 36 thereon arranged a short distance from the film, the face of 95 the bar preferably having a cushion 37 thereon composed of suitable yielding substance to permit the film to be pressed into it, such as asbestos or non-inflammable felt. There is sufficient space between the walls 100 26 and 27 to form a doorway permitting free movement of the film therethrough and the end of the wall 27 is preferably provided with hinge members 38. A door or shutter 39 is provided and movably mounted on the 105 wall 27, and it preferably has hinge members 40 that are connected to the hinge members 38 by means of a hinge pin 41, the door being provided with a spring hinge so as to be automatically closed, the latter being 110 suitably accomplished by means of a coil spring 42 arranged on the hinge pin and having an arm 43 extending against the wall 27, and another arm 44 extending against the outer side of the door so as to 115 act to force the door to the doorway portions of the side walls of the guard, the door having an outwardly extending clamp bar 45 thereon provided on its front face with a cushion 46 similar to the cushion 37, the 120 cushion 46 being brought into contact with the other cushion when the door is closed so as to positively exclude fire from the guard.

For the purpose of holding the door in 125 open position to permit the free operation of the film and permit the door to snap the film and close the doorway when required, a suitable device in the present case comprises a hook 47 connected to the bar 45 and a 130

hook 48 mounted on the guard, as by means of an arm 49 secured to the wall 27. A link 50 is provided which has loops 51 and 52 on its opposite ends respectively, one loop being connected to the hook 47 and the other to the hook 48, the link being composed of suitable material so as to be either fusible or combustible, the link in some cases being composed of the kind of material of which the film is composed so as to readily ignite and burn away and thus permit automatic closing of the fire-door, the link being arranged in proximity to one of the guide rolls or a feed wheel of the machine in order that the film shall positively pass in proximity to the link to insure that the flame consuming the film shall reach the link.

It should be understood that the means for restraining the action of the movable part of the fire-extinguisher or guard and the particular arrangement thereof are not limited to the particular form and arrangement described, and it will be obvious that the movable fire-door is not of necessity a hinge door; and within the scope of the accompanying claims various modifications in the details of construction and arrangement of parts, and combinations thereof, may be varied, as for instance different guards may require different shapes to conform to the structure to which they may most conveniently be secured.

In practical use, in case the film ignites it will be consumed in both directions from the point of ignition and when the fire reaches the vicinity of the controlling device or link 50 the device is affected or ignited and practically destroyed so as to release and permit automatic action of the fire-door before the fire reaches the doorway of the guard, the cushion 46 being brought against the adjacent portion of the film and forcing the latter to the cushion 37, so that the film becomes embedded in the two cushions and permits the contact of the cushions at the edges of the film, the result being that when a flame reaches the bars 36 and 45 the fire becomes extinguished, since the film is incapable of combustion where it is clamped between the two bars and atmospheric air excluded. The operator may readily open the door to gain access to the end of the film after the fire is extinguished and draw it out to enable him to repair the film in the usual manner, after which a new restraining device should be applied for holding the door open to permit free movement of the film.

Having thus described the invention, what is claimed as new is—

1. A film - fire - extinguisher including a guard having a doorway and an abutment projecting from one side of the doorway, a door movably mounted on the guard to engage the walls of the doorway and hav-

ing an outward-extending clamp bar to engage the abutment, impelling means for automatically moving the door, and a fuse for restraining action of the impelling means.

2. A film - fire - extinguisher including a guard having a doorway for the passage of a film, one side of the doorway being provided with a non-combustible yielding face, and a door on the opposite side of the doorway supported for movement to close the doorway and having a non-combustible yielding face to be carried to the film and force the film to be embedded into the two yielding faces.

3. A film - fire - extinguisher including a guard having a doorway therein for the passage of a film, the guard having an abutment thereon projecting outward from one side of the doorway and provided on its front with a non-combustible cushion, a door mounted on the guard and movable to close the doorway and having an outward-extending clamp bar thereon provided on its front with a non-combustible cushion to be carried to the cushion of the abutment for embedding the film in the cushions, and means for automatically closing the door.

4. A film - protector comprising a guard having a fire-wall provided with a doorway for the passage of a film, a door hinged to the wall to close the doorway and provided with a hook, a hook mounted on the fire-wall, a spring having engagement with the fire-wall and the door for moving the door to closed position, and a link connected to the two hooks and holding the door in open position, the link being destructible by the action of a flame on the film.

5. A film-protector comprising two side walls, a fire-wall and a guard wall connected to the side walls, the guard wall having a hook thereon, a door adapted to extend from one to the other of the walls and rest on the side walls between the fire-wall and the guard wall, the door having a hook thereon, a spring-hinge connecting the door with the guard wall to move the door to the fire-wall, and an inflammable and combustible link connected to the two hooks and holding the door away from the fire-wall.

6. A moving-picture projecting machine including a movable picture-film, a fire-wall supported in proximity to the picture-film and having an abutment bar thereon adjacent to the picture-film, the bar having a non-inflammable cushion thereon and presented to one side of the picture-film, a fire-door movably supported and automatically acting to coöperate with the fire-wall and having a clamp bar thereon to be carried thereby substantially to the opposite side of the picture-film, the clamp bar having a non-inflammable cushion thereon and presented to the picture-film to be forced into contact with the latter and the cushion of the abut-

ment bar, for embedding and clamping the picture-film in and between the two cushionings, and means for restraining the fire-door from action and controlled automatically to release the fire-door for action.

7. In a picture-projecting machine having means for moving a film, the combination with the machinery frame of the machine, of a fire-wall supported in the machinery frame and extending to one side of the path of movement of the film and having a yielding non-inflammable end, a fire-door hingedly supported beyond the opposite side of the path of movement to be swung to the fire-wall and provided with an actuating spring and also a yielding non-inflammable end to engage the non-inflammable end of the fire-wall, and a restraining device having operative connection with the door to prevent action of the spring, said device being combustible.

8. In a film-fire-extinguisher, a guard comprising two side walls spaced apart and a fire-wall and a front wall spaced apart and connected to the side walls, the guard having a supporting base, the end of the fire-wall adjacent to the front wall having an abutment bar thereon provided with a yielding non-combustible front, the front wall having a hook supported thereon, a fire-door movably mounted on the front wall and adapted to extend along the front of the side walls and to be moved to the adjacent end of the fire-wall, the end of the fire-door having a clamp bar thereon provided with a yielding non-combustible front to engage

the yielding front of the abutment bar, said door having also a hook thereon, and a spring having engagement with the front wall and the fire-door to move the fire-door to the fire-wall, in combination with a bar of combustible material to be connected with the two hooks for holding the fire-door away from the fire-wall.

9. In a film-fire-extinguisher, a guard comprising two side walls spaced apart and a fire-wall and a front wall spaced apart and connected to the two side walls, the guard having a supporting base, the end of the fire-wall adjacent to the front wall having an abutment bar thereon provided with a yielding non-combustible front, the front of the front wall having a hook thereon, a fire door hingedly connected to the front wall and adapted to extend along the front of the side walls to the fire-wall, the end of the door having a clamp bar thereon provided with a yielding non-combustible front to engage the yielding front of the abutment bar, said door having also a hook thereon, and a spring having engagement with the front wall and the door to swing the door to the fire-wall, in combination with a bar of combustible material to be connected to the two hooks for holding the door away from the fire-wall.

In testimony whereof, I affix my signature in presence of two witnesses.
